(57) **CLAIM**

The ornamental design for a 3D printer leveling sensor, as shown and described.

DESCRIPTION

The patent or application file contains at least one drawing executed in color. Copies of this patent or patent application publication with color drawing(s) will be provided by the Office upon request and payment of the necessary fee.

- 1 . 3D printer leveling sensor
  - 1.1 is a Front, Top, Right Perspective view of our design;
  - 1.2 is a Front view thereof;
  - 1.3 is a Back view thereof;
  - 1.4 is a Top Plan view thereof;
  - 1.5 is a Bottom Plan view thereof;
  - 1.6 is a Left view thereof;
  - 1.7 is a Right view thereof;
  - 1.8 is a Front, Bottom, Right Perspective view;
  - 1.9 is a Front, Bottom, Right Perspective view of the leveling sensor in an alternate configuration of use where the pin is retracted;
  - 1.10 is an Exploded view of 1.1;
  - 1.11 is a Front, Top, Right Perspective view of the leveling sensor in an alternate configuration of use where the mount has been rotated 90 degrees;
  - 1.12 is a Front, Top, Right Perspective view of the leveling sensor in an alternate configuration of use where the mount has been rotated 180 degrees;
  - 1.13 is a Front, Top, Right Perspective view of the leveling sensor in an alternate configuration of use where the mount has been rotated 270 degrees; and
  - 1.14 is a Front, Top, Right Perspective view of the leveling sensor in an alternate configuration of use where the mount has been rotated 360 degrees.
- Portions of the 3D printer leveling sensor shown in red form no part of the claimed design.
